UNITED STATES PATENT OFFICE.

GEORGE SANDERS SWYGERT, OF COLUMBIA, SOUTH CAROLINA.

FILING-GAGE.

1,353,089.

Specification of Letters Patent. Patented Sept. 14, 1920.

Application filed February 17, 1919. Serial No. 277,549.

To all whom it may concern:

Be it known that I, GEORGE S. SWYGERT, a citizen of the United States, residing at Columbia, in the county of Richland and State of South Carolina, have invented new and useful Improvements in Filing-Gages, of which the following is a specification.

This invention relates to tools designed for use in fitting the valves of internal combustion engines, and more particularly valves of that type which are opened by a push rod operating against the stem of the valve. When new valves are installed, or old ones are ground, it is important to again obtain a correct clearance between the valve stems and the push rods in order that there may be no loss of power or irregularity of engine action, and hence the present invention has been designed to provide a holder and a gage for the valve to enable the end of the stem to be filed to reduce its length to obtain the proper clearance between the end of the valve stem and the push rod.

The object stated is attained by means of a novel combination and arrangement of parts to be hereinafter described and claimed, and in order that the same may be better understood, reference is had to the accompanying drawing forming a part of this specification.

In the drawing,

Figure 1 is a perspective view of the tool, and

Fig. 2 is a central longitudinal section thereof showing the manner in which it is used.

Referring specifically to the drawing, 5 denotes a handle or shank of suitable length and external contour so that it may be conveniently grasped with one hand and firmly held. To the outer end of the shank is rigidly secured a gage block 6 of metal. The shank has a central longitudinal bore 7

which is continued through the gage block. The bore therefore extends throughout the 45 entire length of the tool and opens through the respective ends thereof. The outer face of the gage block through which the bore opens at one end is case-hardened, and perfectly flat and perpendicular to the bore. 50 On one side of the gage block is a threaded opening which extends to the bore and is fitted with a set screw 8.

Fig. 2 illustrates the manner in which the tool is used. The stem 9 of the valve 10 is 55 inserted into the bore 7 and advanced until its end projects from the face of the block 6 a distance corresponding to the amount of metal to be trimmed off. The stem is locked in this position by the set screw 8. The projecting end will, preferably, be filed off, although other convenient operation may be resorted to. The block 6 acts as a gage, the file 11 being operated until the projecting end of the valve stem has been filed off 65 squarely and the stem end is flush with the face of the block. The bore opens through the rear end of the shank so that the valve stem may be inserted from this end, leaving the valve head on the outside. The device 70 can be used in a vise, or it may be held by hand, and as it is simple in construction it can be easily and cheaply produced.

I claim:

A filing gage for valve stems, comprising 75 a shank, a gage block carried by one end of the shank, said shank having a longitudinal bore opening through opposite ends of the shank and continued through the block to the outer end thereof to receive the valve 80 stem, said end being flat and perpendicular to the bore, and means for locking the valve stem in the bore.

In testimony whereof I affix my signature.

GEORGE SANDERS SWYGERT.
